UNITED STATES PATENT OFFICE.

GEORGE J. WOODHOUSE, OF OELWEIN, IOWA.

WATER PURIFIER FOR STEAM BOILERS.

Application filed April 19, 1921. Serial No. 462,521.

To all whom it may concern:

Be it known that I, GEORGE J. WOODHOUSE, a citizen of the United States of America, and a resident of Oelwein, Fayette County, 5 Iowa, have invented certain new and useful Improvements in Water Purifiers for Steam Boilers, of which the following is a specification.

My invention relates to water-purifiers for 10 steam-boilers, and the object of my improvement is to provide means for removing solid impurities from water while being preheated and prior to its delivery to a steam-boiler.

This object has been accomplished by the 15 means which are hereinafter described and claimed, and which are illustrated in the accompanying drawings, in which Fig. 1 is a vertical longitudinal section of a furnace containing a tubular steam-boiler in elevation with my improved water-purifying device in circulatory communication therewith; Fig. 2 is a cross-section of said boiler and said device taken just anterior to the rear water-leg and the rear partition of the 20 device; Fig. 3 is a cross-section of the forward part of the separating drum with the forward water-leg being shown mostly in elevation, and Fig. 4 is a cross-section of the settling-chamber of the device and of the 25 mud-drum in communication therewith.

Similar numerals of reference denote corresponding parts throughout the several views.

My improved water purifying device may 30 be employed in connection with any desired type of steam-boiler, but for purposes of illustration, I have shown it in circulatory communication by means of forward and rear water-legs 11 and 13 with ports 10 and 40 12 respectively in the forward and rear parts of the bottom of a separating-drum 1 positioned thereabove longitudinally. The boiler 14 is of the Babcock and Wilcox inclined water tube type mounted within a furnace 45 15 having the usual supporting piers and baffling wall. The preheating-drum 1 is preferably in the form of an elongated horizontal closed cylinder having a cross partition near its forward end enclosing a narrow 50 receiving-chamber 2 having an inlet-pipe 3 in communication with a regulated source of water-supply not shown.

The numeral 8 denotes another cross-partition positioned a distance forwardly of the 55 rear end of said drum. This partition extends from the bottom of said drum but

about half way upwardly into the drum. The partition thus divides off a settling-chamber 4 at the rear end of the drum which has in its bottom depending tubes 5 leading 60 into a horizontally-disposed mud-drum 6 having a blow-off cock 7.

Said forward partition and the forward head of the drum 1 are connected and supported by means of stay-bolts as shown, and 65 both of said partitions are orificed in line to receive the forward and rear ends respectively of a plurality of water-tubes 9 positioned in the lower part only of said drum and placing in communication said chambers 2 and 4.

The separating-drum 1 is enclosed within the upper part of said furnace 15, and subjected to the direct heat thereof in such a manner as to preheat its contents before delivery to the tubular boiler 14.

Feed-water delivered through the pipe 3 into the chamber 2 passes thence through the water-tubes 9 and is delivered into the settling-chamber 4. In its passage through 80 said tubes 9, the feed-water is preheated to a temperature corresponding to the working pressure, which causes deposition within the tubes of such elements as carbonate and sulphate of lime or other substances which ordinarily form solid scale within a boiler. Looser or more friable impurities are carried into the settling-chamber 4 where the current is interrupted sufficiently to permit of their precipitation under the action of gravity 85 and to be deposited by way of the tube 5 into the mud-drum 6. The clarified water rising in the chamber 4 passes over the partition 8 into the drum 1 whence it is delivered downwardly with free circulation by means of 90 95 said water-legs 13 and 11.

The scale and other impurities of the feed water are, therefore, by the preheating and separating functions of said purifying-device kept entirely out of the steam-boiler, 100 which obviates frequent cleaning or repairs thereof.

Having described my invention, what I claim as new and desire to secure by Letters Patent, is:

1. In combination, a boiler, a separating-drum positioned thereabove having a closed chamber at one end and having a transverse-partition spaced from the other end, the upper part of said partition being removed, 110 said closed chamber being in communication with a source of water supply, water-

- tubes positioned in the lower part of said separating-drum with their forward ends in communication with said closed chamber and their rear ends traversing said partition, 5 and water-legs effecting communication between the forward and rear ends of said boiler and the forward and rear ends respectively of the lower part of said separating-drum between said closed chamber and 10 said partition.
2. In combination, a water tube boiler, a separating-drum positioned thereabove having a closed chamber at its forward end and a settling-chamber at its rear end, the settling chamber being in communication with the upper part only of said separating-drum, a plurality of water-tubes traversing said separating drum effecting communication between said closed chamber and said settling-chamber, said closed chamber being in 15
- 20

communication with a source of water-supply, and water-legs effecting communication between opposite ends of said boiler-tubes and opposite ends of the lower part of said separating-drum between said chambers. 25

3. In combination, a boiler, a preheating drum at a higher level having a partitioned settling-compartment at one end thereof and in communication therewith above said partition only, said boiler having communication at its opposite ends with adjacent opposite ends of the bottom of said drum, and a conduit traversing the contents of said drum, in communication with a source of water-supply at one end, and in communication with said settling-compartment at the other end of said drum. 30
- 35

Signed at Waterloo, Iowa, this 18th day of March, 1921.

GEORGE J. WOODHOUSE.
